UNITED STATES PATENT OFFICE.

GEORG ZAPF, OF COLOGNE-NIPPES, GERMANY.

ELECTRICAL INDICATING DEVICE.

No. 839,690.

Specification of Letters Patent.

Patented Dec. 25, 1906.

Application filed March 28, 1905. Serial No. 252,566.

To all whom it may concern:

Be it known that I, GEORG ZAPF, engineer, a subject of the German Emperor, residing at Cologne-Nippes, Province of the Rhine, 5 Empire of Germany, have invented certain new and useful Improvements in Electrical Indicating Devices, of which the following is a specification.

In means for protecting conductors against 10 overcharging in which a discharge to the earth takes place without the conductor itself being interrupted, but in which after such a discharge it is necessary or desirable to change or repair certain parts, it is of 15 course felt to be a drawback that the discharge which has taken place is not indicated, and where a large number of safety devices are connected to the conductor the inspector does not know at which of these 20 devices the discharge has taken place. This drawback is most felt in safety devices for subterranean cables, in which the safety devices are not immediately accessible nor easily inspected.

25 The object of the present invention forms a means for indicating and notifying such discharges.

In the drawing, *a* represents an under- 30 ground cable, *b* spark-gap safety devices of any suitable kind which are intercalated in earthed wires *c*. From these wires a wire *d* is branched off, which wire lies above or below the ground, all of which wires *d* lead to a common annunciator *e*, provided with a bell 35 or other signaling device. Preferably these

wires are branched off from the last coils of the resistances *w*, inserted in the earthed wires *c* with the object of diminishing the current strength, the resistance *w* being situated between the conductor *a* and the signaling device *e*. A wire is carried to the earth from the annunciator *e*.

If a discharge takes place at one of the safety devices, the difference of potential arising between the branching point of the 45 respective wire *d* and the earth-pole *E* of the annunciator *e* causes the bell to sound and a corresponding number-flap to drop. The strength of the current passing into the wires *d* may be regulated at will by interposing 50 suitable resistances.

Having now particularly described and ascertained the nature of my said invention and in what manner the same is to be performed, I declare that what I claim is—

Means for indicating the discharge from a spark-gap safety device comprising the combination with a spark-gap safety device intercalated into an earthed wire, of a branch wire connected with the earthed wire and 60 leading to a signaling device, and a resistance arranged between the signaling device and the spark-gap safety device.

In testimony whereof I have hereunto set my hand in presence of two subscribing witnesses.

GEORG ZAPF.
